Primary Examiner — Antoine D Davis(74) *Attorney, Agent, or Firm* — Price Heneveld LLP(57) **CLAIM**

I claim the ornamental design for gradient measuring apparatus, as shown and described.

DESCRIPTION

FIG. 1 is a perspective view of a ball leveler and registered bottom mount;

FIG. 2 is a front view thereof;

FIG. 3 is a side view thereof;

FIG. 4 is a top view thereof; and,

FIG. 5 is a bottom view thereof.

Dashed lines are to show environment and do not form a part of the claimed invention.
